United States Patent Office

Des. 193,412
Patented Aug. 14, 1962

193,412

VENTILATOR

Melvin H. Best, Pasadena, and Clair A. Samhammer, Altadena, Calif., assignors to Williams-Bermuda Corporation, Los Angeles, Calif., a corporation of California

Filed June 15, 1961, Ser. No. 65,600

Term of patent 14 years

(Cl. D62—3)

FIG. 1.

FIG. 2.

FIG. 5.

FIG. 3.

FIG. 4.

FIGURE 1 is a perspective view of a ventilator showing our new design;

FIGURE 2 is a top plan view thereof;

FIGURE 3 is a front elevation;

FIGURE 4 is a bottom plan view thereof; and

FIGURE 5 is an enlarged, fragmentary, sectional view taken along the line 5—5 of FIGURE 2.

We claim:

The ornamental design for a ventilator, as shown.
